UNITED STATES PATENT OFFICE.

PERCY H. THOMAS, OF MONTCLAIR, NEW JERSEY, ASSIGNOR TO COOPER HEWITT ELECTRIC COMPANY, OF NEW YORK, N. Y., A CORPORATION OF NEW YORK.

ELECTRICAL DISTRIBUTION SYSTEM.

No. 908,167.

Specification of Letters Patent

Patented Dec. 29, 1908.

Original application filed November 8, 1904, Serial No. 231,856. Divided and this application filed June 8, 1905.
Serial No. 264,215.

To all whom it may concern:

Be it known that I, PERCY H. THOMAS, a citizen of the United States, and resident of Montclair, county of Essex, State of New Jersey, have invented certain new and useful Improvements in Electrical Distribution Systems, of which the following is a specification.

The object of the present invention is to provide means whereby a circuit containing translating devices may maintain a uniform and unvarying potential when affected by the current from a source of variable electrical supply.

As a convenient and suitable auxiliary means for accomplishing the described result, I may make use of the qualities of the mercury vapor apparatus which, as is well-known, is not affected as regards its voltage by the current flowing through it. By connecting such a mercury vapor device across the supply circuit mains in series with a resistance and placing the circuit containing the translating devices in shunt to the mercury vapor apparatus, I produce a system in which the variations of the supply circuit do not vary the voltage of the translating or receiving circuit, inasmuch as a circuit taken in shunt to the mercury vapor apparatus, arranged as described, must take the voltage of the said apparatus.

A simple embodiment of my invention is illustrated in the accompanying diagrammatic drawing, wherein—

1 and 2 represent supply mains connected with a source (not shown) of variable electrical supply. Across the mains I connect a conductor, 3, connected with a mercury vapor device, 4, and a resistance, 5. In shunt to the vapor device is a circuit, 6, in which are placed translating or receiving devices, 7, 7, of any suitable character.

The vapor device 4 is of well-known construction comprising a hermetically sealed container, 8, and electrodes, 9 and 10, connected, respectively, with lead-wires, 11 and 12. The positive electrode 9 may be of solid material such as iron and the negative electrode 10 is of mercury.

It is a well-known characteristic of vapor apparatus of this kind that its voltage remains constant under wide variations of current. With the connections described, it is evident that the circuit 6 and the trans-

lating devices included therein will receive the same voltage as the device 4 and consequently that a constant potential will be maintained in the circuit 6.

Any other device having the characteristic of maintaining a uniform voltage under variations of current may be substituted for the mercury vapor device 4 illustrated in the drawing. The function of the resistance 5 is that of taking up, the residual voltage traversing the circuit between the mains.

In another application Serial Number 231,856, filed November 8, 1904, of which this application is a division, claims are made upon the method described herein.

I am aware that it has been proposed to utilize in somewhat similar relations devices capable of automatic mechanical movement for the purposes of maintaining constant potential under changes of current, but, so far as I know, no one prior to the date of my invention has utilized for the purposes described herein a device having the inherent property of maintaining a constant potential independent of the current changes. Such a device as that herein described is sensitive in a degree quite beyond anything that is possible with the mechanical devices referred to.

I claim as my invention:—

1. In a system of electrical distribution, mains connected with a source of variable electrical supply, in combination with a conductor spanning the said mains and containing a device having the inherent characteristic of maintaining constant voltage under changes of current, a receiving circuit connected in shunt upon the said device, and a resistance in series included in the circuit across the mains.

2. In a system of electrical distribution, mains connected with a source of variable electrical supply, in combination with a conductor spanning the said mains and containing a vapor device having the characteristic of maintaining constant voltage under the changes of current, and a receiving circuit connected in shunt upon the said device, and a resistance in series included in the circuit across the mains.

3. In a system of electrical distribution the combination with variable potential bus-bars, a path across said bus-bars including a vapor device comprising a hermetically sealed and completely exhausted container

and a plurality of electrodes, one at least of which is a vaporizable reconstructing cathode and a resistance in series therewith, together with a work circuit connected to the 5 terminals of the vapor device.

4. In a system of electrical distribution the combination with variable potential bus-bars, a path across said bus-bars including a vapor device comprising a hermetically 10 sealed and completely exhausted container and a plurality of electrodes, one at least of which is a vaporizable reconstructing cath-

ode and a device adapted to absorb increasing amounts of voltage with increasing current in series therewith, together with a work 15 circuit connected to the terminals of the vapor device.

Signed at New York, in the county of New York, and State of New York, this 5th day of June, A. D. 1905.

PERCY H. THOMAS
